(57) **CLAIM**

The ornamental design for a cleaning foot for a vacuum cleaner, as shown and described.

DESCRIPTION

FIG. 1 is a front perspective view of a cleaning foot for a vacuum cleaner showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The details of the cleaning foot for a vacuum cleaner shown in broken lines form no part of the claimed design.

1 Claim, 7 Drawing Sheets
